ATTORNEY.

UNITED STATES PATENT OFFICE.

DAVID R. RICHARDS, OF ST. LOUIS, MISSOURI.

CAR TRUCK.

Application filed August 14, 1925. Serial No. 50,190.

My invention relates to car-trucks, and, it is a distinct and practical improvement to overcome certain practical objections to, and defects in the rigid type of car-trucks.

5 The object of my invention is to construct a car-truck consisting of side frame members each formed of two opposed sections hingedly connected at their inner ends.

A further object of the invention is to 10 provide the inner ends of the frame sections with slotted openings to receive the hinge pin thereby providing a flexible car frame to eliminate undue friction of the car wheel flanges with the rails when rounding curves.

15 A still further object of the invention is to provide compression springs between each frame section and the bolster to normally hold the frame sections in their extended relation with each other and yet permit flex- 20 ing of the side frames midway their ends in rounding curves.

A further object of my invention is the provision of a car-truck which will possess advantages in points of simplicity and efficiency, and, at the same time prove itself 25 comparatively inexpensive in manufacture.

With the above and other objects in view, as will be apparent hereinafter, the invention consists in the novel features of construction, arrangement and combination of 30 parts hereinafter more fully described and finally pointed out in the claims hereto appended.

Referring to the accompanying drawings 35 forming a part of this specification, wherein like characters of reference denote similar parts throughout the several views:

Fig. 1 is a side elevation of a car-truck embodying the features of my invention.

40 Fig. 2 is a top plan view thereof.

Fig. 3 is a detail of the hinge pin.

Fig. 4 is a detail of one of the bushings.

Fig. 5 is a detail of the hinge connection between the two sections of a side frame.

45 Referring to the drawings, the reference numeral 1 represents the car wheels, 2, the axles and 3, the journal boxes, all of which may be of the ordinary construction.

In carrying out the aim of my invention, I 50 employ two side truck frame members. Each of the truck side frame members consists of two sections 4 and 5. Sections 4 are each provided with the upper arm 6 and the lower

arm 7. The said arms 6 and 7 are provided with slotted openings 8 and 9, respectively. 55 Sections 5 are each provided with the upper arm 10 and the lower arm 11. The arms 10 and 11 are provided with the slotted openings 12 and 13, respectively.

A bushing 14 is positioned in each of the 60 slotted openings 8 and 9 of arms 6 and 7, while a like bushing 15 is positioned in each of the slotted openings 12 and 13 of arms 10 and 11. A suitable hinge pin 16 is receivable in the bushings 14 and 15. The upper end 65 17 of the pin is larger in diameter than the lower end thereof and the lower end of the upper section 17 of pin 16 is screw threaded to receive a nut 18 which is locked against 70 rotation by a suitable key 19 for frictionally holding arms 6 and 10 between the head 20 of pin 16 and the nut 18. The lower end of pin 16 is also threaded and carries a nut 21 which is held against rotation by means of 75 a key 22, said latter nut engaging the lower face of the lower arm 11 of section 5, as clearly shown in Fig. 3. This arrangement of parts, it will be observed, provides a hinged, or flexible connection between the side frame members 4 and 5 which will tend 80 to reduce the binding effect of the car wheel flanges with the rails when rounding curves.

Spanning the space between the two truck side frame members and connecting hinge pins 16 is a lower spring supporting channel 85 plate 23 upon which is mounted four suitable coiled compression springs 24 adjacent each hinge pin 16. Each spring 24 is provided at each end with a suitable cap 25 and an inverted channel plate 26 is seated 90 upon the caps 25 seated upon the upper ends of the springs 24. A suitable bolster plate 27 is mounted upon the upper channel plate 26 and the hinge pins 16, it will be observed, pass through slotted openings at each end 95 of the bolster plate 27 and the upper and lower channel plates 26 and 23.

A suitable male bearing plate 28 having an opening for the hinge pins 16 is fixed to the lower face of the lower channel plate 100 23 and engages a female bearing plate 29 fixed to the upper face of the lower arm 7 of each side frame section member 4.

Each of the vertical members 30 of the side frame members 4 and 5 are provided 105 with one or more horizontally disposed sock-

cts 31. A suitable coiled compression spring 32 is seated in each of the sockets 31 with their inner ends engaging side walls of the channelled bolster plates 23 and 26, as clearly shown in Fig. 5 for normally holding the side frame members 4 and 5 in their extended positions. It will be here observed that the springs 32 will permit the side frame members upon the inside of a curve in the track to move toward each other due to the slotted pin receiving openings 8 and 9 of frame members 4 and slotted openings 12 and 13 of frame members 5 to shorten the distance between the wheels on that side of the truck which overcomes the flange resistance upon the rails, which resistance is great in rigid truck construction. As soon as the truck has rounded the curve, the springs 32 will expand thereby moving the hinged side frame members back to their normal extended position, while the wheels are rolling upon a straight track.

The ends of the arms 6 and 7 of the side frame members 4 are connected by means of the laterally arched connecting members 33. The ends of the arms 10 and 11 of the side frame members 5 are also connected by means of laterally arched connecting members 34, which members or arms 33 and 34 serve to strengthen the inner ends of the arms 6 and 7 and the arms 10 and 11. The connecting members 33 and 34 are arched laterally to permit turning movements of the side members and to prevent striking the arms of the connected side frame members while the truck is rounding a curve.

From the foregoing description, it is evident that I provide a truck, having flexible or hinged side frame members or sections, which will, when rounding a curve, move toward each other on the inside of the curve and remain extended on the outside of the curve due to the slotted openings through which the hinge pins pass and the coiled springs 32. The coiled springs 32 upon that side of the truck which is taking the inside of the curve are compressed in rounding the curve so as to shorten the side frame to bring the wheels closer together, as is manifest and clearly shown in dotted lines in Fig. 2.

The many advantages of the herein described invention will readily suggest themselves to those skilled in the art to which it appertains.

I do not wish to be understood as having limited myself to the exact details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such

changes, or modifications, as may fairly fall within the scope of the appended claims when fairly construed.

What I claim is:

1. A side frame for four wheel car-trucks comprising two substantially like sections having slotted hinge connection at their inner ends for flexibly uniting said sections. 70

2. A side frame for four wheel car-trucks comprising two substantially like frame sections having extending longitudinally slotted arms, and a hinge pin passing through the slotted arms of said sections to provide a unit side frame capable of being shortened upon the inside of a curve and lengthened 80 upon the outside of a curve.

3. A side frame for car-trucks comprising two substantially like sections, a bolt hingedly connecting said sections and said sections having slotted openings for receiving the hinge pin. 85

4. A side frame for car-trucks comprising two separable sections, resilient means for normally holding the sections in their extended relation, means for hingedly connecting said sections at their inner ends and said sections having slotted openings for receiving the means for hingedly connecting the same. 90

5. In a car-truck structure, a pair of 95 wheel supported side frames, said frames each consisting of two sections hingedly united by means of a slot and pin connection, a spring supporting plate, an upper plate yieldingly mounted above said spring 100 supporting plate, resilient means for normally holding the two sections of each side frame in their extended relation and a bolster mounted upon said upper plate.

6. In a car-truck structure, a pair of wheel 105 supported side frames, said frames each consisting of two sections hingedly united by means of a slot and pin connection, a spring supporting plate, a bearing plate connection between the spring supporting plate and 110 one of said side frame sections, an upper plate yieldingly mounted above said spring supporting plate, resilient means for normally holding the two sections of each side frame in their extended relation and a bolster mounted upon said upper plate. 115

7. In a car-truck structure, a pair of wheel supported side frames each consisting of two sections provided with upper and lower inwardly directed arms, the arms of one section adapted to engage the arms of the other section in overlapping relation and said arms being provided with vertically disposed slotted openings, bushings receivable in the slotted openings of the upper arms, 120 bushings receivable in the slotted openings of the lower arms, a hinge pin receivable in said bushings, fixed means for locking said pin against downward displacement, adjustable means to prevent the pin from up- 125 130

ward displacement, a spring supporting channel plate connecting the hinge pins of opposite side frames, a plurality of coiled springs surrounding each pin, an upper channel plate mounted upon said springs and connecting said opposed hinge pins, resilient means interposed between each section of each side frame and the aforesaid

channel plates to normally hold the side frame sections in their extended relation and a bolster plate mounted upon the upper channel plate and having connection with said hinge pins. ¹⁰

In testimony whereof, I have hereunto signed my name to the specification.

DAVID R. RICHARDS.
